UNITED STATES PATENT OFFICE

AUGUST ROOS, OF LUBECK, GERMANY

AUTOGRAPHIC REGISTER

Application filed September 16, 1929, Serial No. 392,753, and in Germany September 26, 1928.

I hereby declare that the following is a full, clear and exact description of my invention, reference being had to the accompanying drawings, which form part of the specification.

My invention relates to that class of autographic registers or manual recorders, in which are usually employed two paper strips led over an exposed writing tablet or block where the desired memoranda is written upon the upper one and duplicated by manifolding material upon the lower one and whence the lower strip is led to a roll of the machine, while the other or upper strip passes out of the machine and is severed into detached checks. The principal feature of my invention is to lead both paper strips in such a way, that when the under or record strip is driven by its operating means, which means are projecting through the casing for that purpose, the upper strip is frictionally engaged by the lower strip, whereas, when the upper strip projecting with its outer end through a slot of the machine, is drawn by hand, the lower strip is not engaged thereby, but remains in its position. In this way I am enabled to have a permanent record on the record strip, and to give to the purchaser a check of any desired length.

A further object of my invention is to avoid the usual carbon sheet interposed between the two strips and to manifold the record in a very clean and exact manner. For this purpose I propose to employ transparent paper for the lower or record strip and to embed into the tablet or block an ink cushion, by which the record strip is written on its under side. The record strip being transparent, the memoranda thereon may be read from the top side in the ordinary manner.

The novelty of my invention will be hereinafter set forth and particularly pointed out in the annexed claims.

In the accompanying drawings Fig. 1 represents a front elevation of the machine, Fig. 2 a detail and Fig. 3 a vertical longitudinal section of the machine on the line 3—3 of Fig. 1.

The same letters of reference are used to indicate identical parts in all the figures.

Both paper strips, the upper strip to be severed into detached checks (which is called in the following text the check strip) and the under or record strip of transparent paper, are carried upon supply rolls, the check strip upon the supply roll *a* and the record strip upon the supply roll *b*. The roll *a* delivers the strip *p* and the roll *b* the strip *q*. Both strips are led thence to a pressure roll *c*, either made of yieldable material, such as of rubber, or it may be mounted yieldingly. The middle spools of the rolls *a* and *b* and the roll *c* are rotatably mounted in the sides of the casing *r*, which is closed by the top or cover *s*. The pressure roll *c* press the strips against the under side of a block or tablet *o*, fixedly mounted in the casing and thence the strips *p* and *q* are led over the front side of the said tablet, where they are passing an aperture *u* provided in the cover *s* so as to enable a salesman or the like to write a memoranda upon the strip *p*. Embedded in the block *o* is an ink-cushion *n*, by which the memoranda is registered on the record strip *q*, from the under side. The inverted letters of the under side of the record strip *q* make a fraud more difficult, but may nevertheless read from the top side without difficulty. Adjacent to the upper and lower edge of the aperture *u* and fixed to the top *s* are guiding rails *l*. Between the said rails *l* a pattern *m* or pattern *m'* of a desired graduation may be inserted, so that by choosing the required pattern the machine may be accommodated to all individual requirements. In a little distance over the upper rail *l* and extending substantially from side to side of the machine is a slot *h*, through which the check-strip *p* projects, so that it may be grasped by hand. The upper edge *i* of this slot is bent inwardly and separates the strips from each other. The lower edge *k* thereof forms a tearing edge, so that the check-strip *p* is adapted to be torn off into checks against this tearing edge *k*. The record strip *q* remains in the casing and is led to a spool *t*, rotatably mounted in the side parts of the casing *r*. The right

hand end of this spool *t* carries a gearing wheel *g*, meshing with a gearing wheel *f*. The wheel *f* is mounted on the block *o* and meshes with a gearing wheel *d*. Fixed to the 5 gearing wheel *d* is a milled disc *e* projecting through a slot *w* of the cover *s*, so that it may be operated and rotated by hand.

The general mode of using the machine is as follows:

- 10 The saleman or the like, having written grasps the strip *p* projecting through the slot *h* and pulls it out of the casing in a desired length. In doing so the strip *p* is stretched and the pressure roll *c* somewhat 15 lifted and removed thereby from the strip *q*, so that the latter is not engaged and remains stationary.
- In order to register the next sale, the disc 20 *e* is rotated. The pressure roll *c* pressing with its normal force creates so much friction between both strips *p* and *q*, that both strips are transported. By this operation the strip *p* projects again through the slot *h* and may as already described be drawn out of the casing 25 in any desired length without engaging the strip *q*.

In this way it is possible to have the record-strip written in a permanent manner, i. e. without distances of the lines written thereon, and without a waste of paper and to furnish the purchaser with a long check. Moreover the addition of the single amounts, registered on the record strip in a permanent manner is facilitated.

30 35 It is to be understood, that the form and construction of my new autographic register may be susceptible of embodiment in various other alternative forms, and that the particular arrangement, which happens to be illustrated in the drawings is not an essential 40 requisite so far as the fundamental and novel features of my present improvements are concerned. Accordingly the privilege is reserved of resorting to all such legitimate 45 changes in the form of construction and relative arrangement of the various parts as may be fairly incorporated within the spirit and scope of the invention as claimed.

What I claim is:

- 50 1. In an autographic registering device of the character described the combination with a casing, means therein for operatively mounting two rolls of paper strips, said paper strips each being unwindable and means in the casing for guiding the strips during unwinding actions, of a pressure roll positioned against the upper strip to normally press it to engagement with the lower strip whereby 55 movement of the latter entails a corresponding movement of the upper strip, said pressure roll being in normal pressing position against the strips for simultaneous movement of both strips, and yieldably movable 60 when the upper strip is pulled to remove the 65

frictional contact between both strips carried by said roll.

2. In a registering device of the character described the combination with a casing and means for operatively mounting a pair of paper strips in roll form therein, said paper strips being unwindable with the free running portions superposed, of operating means engaging with the lower paper strips and operative to cause movement thereof, a reel in the casing for taking up the lower strip, said casing being provided with a slot through which the upper strip projects and a pressure roll normally bearing against the upper strip and constituting means for normally pressing the upper strip into frictional contact with the lower strip whereby movement of the latter entails a corresponding movement of the upper strip, said roll being rotatably movable in abutting relation against the block 1 when the reel takes up the lower strip, and being yieldably movable out of position when the upper strip alone is pulled.

3. In a registering device of the character described having a casing, means in the casing for operatively mounting two strips of paper in roll form for individual unwinding actions and a reel in the casing for taking up one of the strips, said casing being formed with a slot through which the upper strip projects into position where it may be grasped by the user, a yieldably displaceable pressure roll normally engaging said strips to cause frictional contact therebetween, gear mechanism on a block in the casing engaging one of the strips to cause movement thereof which movement is transmitted through frictional engagement to the other strip, said last-mentioned strip being effective under the influence of tension thereon to cause said pressure roll to be moved into position where it is rendered ineffective to create frictional contact between the strips whereby said last-mentioned strip is rendered independently movable of the other strip.

4. In a registering device of the character described having independently positioned rollers for carrying rolls of paper strips rotatably movable and superposed with respect to each other, a block for carrying a gear mechanism for normally pulling the strips forwardly of the casing, and yieldable pressure means rotatably mounted in the casing abutting the block and normally disposed against the superposed strips to frictionally engage the same between the block and said means upon movement of the lower paper, and disposed to be moved out of abutment against the block when the upper strip is pulled independently of said lower strip.

In testimony, that I claim the foregoing as my invention I have signed by name.

AUGUST ROOS.
